STUART PARMELEE MILLER, OF ENGLEWOOD, NEW JERSEY, ASSIGNOR TO THE BARRETT COMPANY, OF NEW YORK, N. Y., A CORPORATION OF NEW JERSEY

PRODUCTION OF HIGH AND LOW CARBON PITCHES

Application filed December 29, 1927. Serial No. 243,309.

This invention relates to the simultaneous production of high carbon pitches and of low carbon pitches of regulated high carbon and low carbon content at coke oven or other coal 5 distillation plants.

In my companion applications, Serial No. 243,305 and Serial No. 243,307, I have described the separate recovery of low carbon tar and of high carbon tar respectively from 10 the gases given off during the early and the later periods of the coke oven or other coal distillation operations, and the distillation of such low carbon tar or of such high carbon tar for the production therefrom of a low 15 carbon pitch or a high carbon pitch.

The present invention provides an improved method whereby both a high carbon pitch and a low carbon pitch of independently regulated high carbon and low carbon 20 content can be simultaneously produced at a coke oven plant.

According to the present invention, I provide for separately collecting the gases from the individual ovens or retorts during the 25 early portion of the coking or gas making operation, and for separately collecting the gases from the individual ovens or retorts during the later period of the coking or gas making operation, and for separately collecting the 30 gases from the intermediate period of operation, and, in connection with each such separate collecting system, I provide means for separately collecting and keeping separate the low carbon tar, the intermediate carbon tar, and the high carbon tar obtained 35 simultaneously from the respective gases; and

I subject the low carbon tar and the high carbon tar separately to distillation to produce simultaneously a low carbon pitch and a high carbon pitch of independently regulated low carbon and high carbon content. A pitch of intermediate carbon content can also be produced from the tar given off during the intermediate period of operation.

45 In my companion applications, Serial No. 243,306 and Serial No. 329,197, I have described the production of composite pitch compositions by distilling low carbon tar or high carbon tar to produce low carbon pitch 50 or high carbon pitch and blending the respec-

tive pitches with tar to give composite products of low carbon content or high carbon content.

The present invention provides improvements in the simultaneous production of such composite high carbon and low carbon pitch compositions whereby the carbon content of the compositions can be independently and simultaneously regulated at the coke oven or other coal distillation plant.

According to the present invention, instead of providing two collector mains, one of which must receive all of the gases which are not directed into the other, I provide three collector mains so that I can collect in one the gases from any desired initial period of the coking or gas making operation, in another the gases from any desired final period of the operation, and a third in which the gases from the intermediate portion of the operation can be collected. In this way, the low carbon tar from the initial period of operation can be independently regulated and the high carbon tar from the final period of operation can be independently regulated. Furthermore, when a tar of intermediate composition and properties is desired, and a pitch of intermediate composition and properties, the gases from only the intermediate period of operation need be separately collected and the tar 80 separated therefrom and subjected to distillation to give a new pitch composition which is free both from the lower carbon pitch of the initial period of operation and from the higher carbon pitch of the final period of operation.

In connection with the three collector mains, I provide three condensing systems for condensing the lighter tars which will be respectively low carbon, intermediate carbon 90 and high carbon light tars.

There are thus provided, in the practice of the present invention, three separate and distinct kinds of tar, differing in their carbon content, specific gravity and other properties; 95 together with a heavy tar from the collector main and lighter tars from the condensers in each case; and by distillation of these respective tars, pitches are produced of high, low or intermediate carbon content and other 100

properties; and these pitches can be varied independently and can be blended with a wide range of other products to give intermediate and composite pitch compositions covering practically the entire range from the highest carbon pitches to the lowest carbon pitches and including intermediate fractionally separated tars and pitches which, although they may have a carbon content the same as or similar to that of the total tar when collected together, nevertheless differ from total tar of the same carbon content and for some purposes form more valuable products.

In addition to providing for the independent production and regulation of the pitches, the present invention provides for the independent regulation of the oils produced by distillation of the respective tars. The composition of the tar given off during the coking period changes from a low carbon tar during the early period of operation to a high carbon tar during the late period of operation. The oils distilled from the low carbon tar are of lower specific gravity and the oils distilled from the high carbon tar are of higher specific gravity. The oils distilled from the low carbon tar are higher in tar acids or phenols, while those distilled from the high carbon tar are lower in tar acids or phenols. The oils distilled from the intermediate tars, produced during the intermediate period of operation, are of an intermediate character and distinguished from both the higher gravity oils produced from the high carbon tars and the lower gravity oils produced from the low carbon tars.

The separate distillation of the high, low and intermediate carbon tars can be carried out in ordinary tar stills, but is advantageously carried out at the coke oven or gas retort plant by bringing the respective tars into direct and intimate contact with the hot coke oven or other coal distillation gases at a sufficient temperature to effect rapid distillation. The gases employed for the distillation are advantageously those corresponding to the gases from which the respective tars are separated, so that, for example, the high carbon tar is distilled by gases from which high carbon pitch will be separated, and the low carbon tar is distilled by gases from which low carbon pitch will be separated. By operating in this way, the pitch produced by the distillation and the pitch separated from the gases employed for the distillation will be pitch of the same or similar carbon content and pitches of regulated high or low or intermediate carbon content can be produced.

In some cases, however, such close regulation of the carbon content is not required and the total gases from a selected number of ovens can be employed for the distillation of the respective tars. In such case, the pitch separated from the gases will have an aver-

age carbon content and will or may modify the carbon content of the pitch produced. For example, if high carbon tar is distilled in the total gases from a selected number of ovens the pitch produced will be a composite product made up of the high carbon pitch resulting from the distillation of the tar and the lower carbon composite pitch separated from the gases, giving a composite total pitch product of lower carbon content than would be produced if the high carbon tar were distilled in gases from which high carbon pitch could be separated. Similarly, if low carbon tar is distilled in the total gases from a selected number of ovens the carbon content of the resulting pitch will be somewhat higher than it would be if the low carbon tar were distilled in rich gases from which low carbon pitch of similar carbon content could be separated during the distillation. The selection of the carbon content of the tar distilled and of the gases employed for the distillation enables a wide range of pitch products of regulated high or low carbon content to be produced.

For the distillation of all three tars, I provide three separate stills or distilling mains or boxes into which the tar is introduced and in which it is intimately brought into contact with the hot coke oven or other coal distillation gases, and into which the gases from a selected number of ovens or retorts are introduced for effecting the distillation. It is sometimes advantageous to distill separately the heavy tar from the collector main and the lighter tar from the condensers, since the heavier tars give a pitch with less distillation, and the lighter tars give increased oil yields for the tar distilled. A greater or a smaller number of stills may be provided depending upon the particular operation.

Where it is desired to distill simultaneously both the heavy tar and the lighter tar, more than three distillation stills may be provided; or the products can be collected and stored and subjected to distillation at different times in the same stills.

The operation of the three collector mains may be much the same as in systems where only a single main is provided. That is, the gases in the individual collector mains may be cooled by the introduction of ammonia liquor, or the circulation of ammonia liquor and tar therethrough, so that there will be thrown down a greater part of the tar as a heavy tar which is drawn off separately from each of the collector mains and kept separate for subsequent separate distillation. The lighter tars or tarry oils from the condensers are also kept separate from each other, and a plurality of products may be obtained from the different stages of the same condensers, which separate products may also be kept separate and separately distilled.

In order that the distillation of the respec-

tive tars may be carried out to give not only pitches of regulated carbon content and other properties, but also a high yield of the individual oils, and in order that the oils may be obtained in a relatively clean state, that is, relatively free from heavy tar and pitch constituents, the gases employed for the distillation are advantageously cleaned to remove therefrom all or the greater part of the tar "fog" or suspended tar and pitch particles. This can readily be effected for example, by passing the gases, subsequent to their employment for distillation, through an electrical precipitator at a high temperature, or through a pitch scrubber at a high temperature. It can also be advantageously effected by subjecting the gases employed for the distillation to such intimate contact with the tar or pitch being distilled as to effectively scrub the gases and free them from all or the greater part of the suspended tar and pitch constituents, leaving only or mainly volatile oils in vapor form in the gases leaving the still. Such cleaned gases and vapors, after separation of entrained heavy particles of pitch by settling or by a mechanical separator, will, on cooling, give clean or relatively clean oils which will differ from each other with the particular tar being distilled, and which can be fractionally condensed to give a wide variety of different oil distillates, differing from each other in specific gravity, viscosity and composition.

The invention will be further described in connection with the accompanying drawings, which illustrate, in a somewhat conventional and diagrammatic manner, one form of apparatus embodying the invention and adapted for the carrying out of the process of the invention.

In the accompanying drawings

Fig. 1 is a plan view showing part of a coke oven plant, with parts broken away;

Fig. 2 is a partial elevation of the plant of Fig. 1;

Figs. 3 and 4 are sectional views showing modified forms of stills;

Fig. 5 shows a baffle tower used on one of the stills, and

Fig. 6 shows an electrical precipitator arranged for use on one of the stills.

In the drawings, the coke ovens 1 have the usual uptake pipes 2 but these uptake pipes are connected with three separate collector mains 3, 4 and 5 and have valves 6, 7 and 8 for connecting each uptake pipe with any one of the three mains.

Three cross-over mains 9, 10 and 11 lead from the three collector mains to condensing systems, only one of which, that connected to the cross-over main 11, is shown. The cross-over main 11 leads to a common main 12, connected to two or more cross-over mains at different parts of the battery. The main 12 leads to condensers 13 and 14 which may be

of the indirect or direct type but which are shown as of the direct type with provision for the introduction of cooling liquids through spray pipes 15 at the top of the condensers. From the condensers, the gases escape through line 16 to exhauster 17 and to the ammonia absorber, and if desired to the benzol scrubber (not shown).

The three collector mains are shown as cooled by the introduction of ammonia liquor supplied through the pipe 20 and sprayed into the uptake pipes through spray nozzles 18 and into the collector mains through spray nozzles 19.

Each of the collector mains is provided with a separate tar draw-off for drawing off therefrom and keeping separate the tar which collects therein. Only one such tar collecting system for one of the mains is shown in Fig. 1, the others being omitted for simplicity of illustration. The tar from the collector main 4 flows out therefrom through the center box and the pipe 23 to the separating tank or decanter 24 for separating the ammonia liquor from the tar, and the tar then flows to the tank 26 and the ammonia liquor to the tank 25.

From the tar tank 26 the tar is pumped through line 28 by pump 29 to pipe 30, leading to still 32 shown as arranged on the opposite side of the coke oven block from that at which the collector mains are located. The still 32 is one of three stills 31, 32 and 33, provided for distilling the tar from each of the collector mains 3, 4 and 5, or the tar from the condensers connected to these respective collector mains.

At the end of the cross-over mains 11 and 12 is provided another tar separator or decanter 35 for separating ammonia liquor from tar, the ammonia liquor being drawn off through pipe 36 and the tar to tank 37 from which it may be, if desired, pumped by pump 38 through line 39 to line 30 and to the still 32 for distillation.

The condensers 13 and 14 are shown as having a single tar separator or decanter 40, for collecting all of the tar from both condensers together, although the tars from the separate condensers may, if desired, be kept separate. The ammonia liquor separating in the separator 40 is collected in tank 41 while the tar is collected in tank 42 and may, if desired, be pumped back by pump 43 through the line 44 to the line 30 and to the still 32.

Ammonia liquor from the tank 25 may be pumped by pump 45 through line 46 and line 20 to the collector mains. Ammonia liquor from the tank 41 may be worked up for recovery of ammonia.

Each of the stills is connected to a plurality of uptake pipes leading from different ovens so that the gases from a larger or smaller number of ovens can be passed into each of the stills. These uptakes are indicated at

48, but we are not limited to the number shown. The tar enters the still at one end through tar inlet 49 and the pitch leaves the still at the other end through pitch outlet 52 and passes to pitch storage tank 53 or to other place of disposal or use.

5 Each still is provided with means for atomizing or spraying the tar and pitch to insure intimate contact thereof with the hot 10 gases coming from the ovens into the still. In Fig. 3 discs 51 are shown mounted on a shaft 68 which is provided with an electric motor 67. The level of liquid is maintained 15 preferably so that the discs 51 dip slightly below the level when the still is in operation. By means of the electric motor, the shaft 68 and discs are rotated at a high rate of speed 20 so that the tar is thrown into the space above the discs in a finely divided state and in great 25 quantity. The particles of tar are so intimately mixed with the gases entering the still from uptake 48 that the tar fog and other entrained matter is removed from the gases substantially completely, this being accomplished partly in the distilling main and partly as the gases pass up through the settling 30 spaces above the still. In Fig. 4 a rotating roll 51a is used instead of the discs to atomize or spray the tar into the gases. Fig. 5 shows 35 a preferred arrangement of a settling tower above the still. In Fig. 5 the tower 63 is shown as equipped with baffles 64 to aid in the removal of the tar fog. Tar may be introduced through tar line 65 to preheat the 40 tar as it passes down over baffle 64. In Fig. 5 is shown an electrical precipitator 66, for the purpose of removing any entrained matter from the gases, which will be returned to the still.

45 The gas and oil vapor resulting from the distillation leaves the still through gas outlet pipe 55 and passes through a main or pipe 56 to condensers 57 and 58. If fractional condensation of the oils is desired, a plurality of condensers will be employed and the condensates will be kept separate. In the apparatus illustrated, the two condensers 57 and 58 discharge the condensed oils into a common tank 59. The condensers are shown 50 as of the direct type cooled by the introduction of a cooling liquid, such as water or ammonia liquor, which can be separated from the oils in the separating tank 59 and the oils collected in tank 61 and the ammonia liquor 55 in tank 60. The gases leaving the condensers pass to the exhauster 17 along with the gases from the condensers 13 and 14.

60 While only one still and one system connected therewith has been illustrated in detail and described, it will be understood that each of the stills will have similar connections and condensers so as to provide three complete and independent systems for collecting tar from the gases in three collector 65 mains and three condensing systems and for

returning the tar from either the collector mains or from the condensers, or any desired part of the tar from each system, to a still therefor, in which the tar is distilled and pitch produced and distillate oils recovered. 70

In the operation of the apparatus and the carrying out of the process, the gases from any desired initial period of operation of the coke ovens will be collected in one of the mains, for example, the main 3, and cooled 75 therein to give a low carbon tar, and the gases leaving the collector main will be further cooled in the cross-over main and in the condensers to give lighter tars or tarry oil which 80 will likewise be characterized by a low carbon content.

The gases from any desired final portion 85 of the coking operation can be collected together in one of the collector mains, for example, the main 5, and cooled therein to 90 separate a high carbon tar, while lighter tars of high carbon content will be recovered from the condensers connected to this collector main.

95 So also, the gases from the intermediate portion of the coking operation which remain after the desired initial portion of the gases and the desired final portion of the gases have been separately collected, pass to the third collector main 4 where they are cooled and tar separated therefrom, and the gases further cooled in the condensers for the separation of lighter tar. This tar from the intermediate period of operation will be of intermediate carbon content. If it is desired 100 to produce an intermediate tar of regulated carbon content, this can readily be accomplished by regulating the intermediate period of operation of the ovens, from which the gases are collected in the intermediate collector main, and allowing the remaining portion of the gases given off during the initial and the final periods of operation to be collected in the other two mains or even in one 105 of the mains.

110 The high, intermediate and low carbon tars collected from the collector mains, or from the end of the cross-over mains, or from part or all of the condensers, are kept separate 115 and part or all of these tars can be subjected to distillation in the respective tar stills to produce therefrom high, intermediate or low carbon pitches and distillate oils corresponding to the tars distilled. Either the 120 heavy tar from the collector main can be distilled by itself, or the lighter tar from the condensers, or the total tar from the collector main and condensers may be distilled together, for example, the total low carbon tar 125 can be distilled to give a low carbon pitch, and distillate oils of relatively low specific gravity. The high carbon tar can similarly be distilled to give high carbon pitch and distillate oils of relatively high specific gravity; 130

while the intermediate tar will give intermediate pitch and oils. The provision of three collector mains permits the carbon content and other properties of the low carbon 5 pitch and of the high carbon pitch to be simultaneously and independently regulated, or enables an intermediate pitch of regulated properties to be produced.

When the gases are effectively scrubbed 10 and cleaned by the spray in the still, and the entrained particles are separated, for example, by a baffle tower or electrical precipitator, the oils condensed from the gases will be clean oils free or substantially free from 15 heavy tar and pitch constituents. These oils, by fractional condensation, will give heavier and lighter oil fractions differing from each other, depending upon the kind of tar from which they are distilled.

20 The present invention is of particular advantage in connection with coke oven plant operations. It is also applicable, in its broader aspects, to other coal distillation plants where the gases can similarly be separated to

25 give low carbon tars and high carbon tars during the early and later periods of operation, together with an intermediate tar from the gases given off during the intermediate period of operation.

30 The present invention also enables a wide range of blended pitch products to be produced such as described, for example, in my companion applications Serial No. 243,308 and Serial No. 243,306. In addition, the

35 present invention enables blended pitches to be produced from the pitch of intermediate carbon content obtained by separate distillation of the tar of intermediate carbon content separated from the coke oven or other

40 coal distillation gases during an intermediate period of operation. With high, low and intermediate carbon pitches available, and with high, low and intermediate carbon tars available, both heavier tars from the collector

45 mains and lighter tars from the condensers, there are available at the coke oven or other coal distillation plants, a wide range of pitches and tars which can be blended in a wide range of proportions to form blended

50 pitch compositions having a wide range of carbon content. The new intermediate carbon content pitch can, for example, be blended with tar of intermediate carbon content or with tar of high or low carbon content to 55 give new composite pitch compositions.

The carbon content of the pitch produced can be regulated not only by regulating the carbon content of the tar distilled but also in part by employing gases from an early, 60 intermediate or late portion of the coking operation from which low, intermediate or high carbon pitches will be separated and become blended with the pitch residue from the distillation. For example, the still employed 65 for the distillation of high carbon tar may be

connected only with ovens which are at an advanced stage of the coking period so that high carbon pitch will be separated from them during the distillation. A high carbon pitch of regulated high carbon content 70 can thus be obtained. Similarly the distillation main or still in which low carbon tar is distilled may be connected only to ovens which are at an initial stage of the coking period so that low carbon pitch will be separated from the gases during the distillation. In other cases the total gases from a selected number of ovens can be employed for distilling either the high or the low carbon tar in which case the high carbon pitch and the low 80 carbon pitch produced will have their respective carbon contents lowered or increased by the pitch separated from the total gases employed for the distillation. In this way 85 pitches of varying and regulated carbon content can be produced and a wide range of different pitch products can be simultaneously produced.

I claim:

1. The method of producing high free carbon pitch and low free carbon pitch of independently regulated free carbon content from coke oven or other coal distillation gases, which comprises collecting separately the gases given off during a regulated early portion of the coal distillation in such oven or retorts, collecting separately the gases given off during a regulated later period of distillation in such ovens or retorts, which earlier and later periods are independently regulated and together are less than the total period of distillation in the ovens or retorts, keeping separate the respective gases collected during the early period of distillation and those collected during the later period 95 of distillation, cooling the respective gases 100 to separate tars of different free carbon content, and separately distilling the respective tars to produce pitches of different free carbon content.

2. The method of producing coal tar pitch of intermediate free carbon content from coke oven and other coal distillation gases, which comprises collecting separately the gases given off during an intermediate period of the coal distillation in such ovens or retorts, which intermediate gases do not include the gases produced during the early period of distillation, and also do not include the gases produced during the later period of distillation, in such ovens or retorts, cooling such intermediate gases while maintained separate from the other gases to separate tar therefrom, and subjecting such tar by itself to distillation to produce pitch therefrom.

3. The method of producing lower, intermediate and higher free carbon pitches which comprises collecting separately the gases given off during the early, intermediate and later periods of the coal distillation in coal

distillation ovens or retorts, separately cooling the respective gases to separate therefrom tars of lower, intermediate and higher free carbon content, and subjecting such tars separately to distillation for the production therefrom of pitches of lower, intermediate and higher free carbon content.

4. The method of producing high free carbon and low free carbon pitches of independently related free carbon content, which comprises collecting separately the gases given off during a regulated early period and during an independently regulated later period of the distillation of coal in ovens or retorts, cooling such respective gases to separate tars of low and high free carbon content therefrom, and subjecting the tars so produced separately to distillation by bringing them into direct and intimate contact with hot coal distillation gases to produce pitches therefrom.

5. The method of producing pitches of lower and higher free carbon content at coal distillation plants, which comprises collecting separately the gases given off during an early period, an intermediate period, and a later period of the distillation of the coal in the ovens or retorts of the plant, cooling the respective gases to separate therefrom tars of lower, intermediate and higher free carbon content, and separately subjecting the tars of lower and higher free carbon content to distillation by bringing them into direct contact with hot coal distillation gases to produce higher and lower free carbon pitches therefrom.

6. The method of producing coal tar pitch of intermediate free carbon content, which comprises collecting separately the gases given off during an intermediate period of the distillation of coal in the ovens or retorts of a coal distillation plant, which gases are free or substantially free from gases given off during the initial and final period of coal distillation in these ovens or retorts, cooling the gases given off during such intermediate period to separate tar of intermediate free carbon content, and subjecting such tar to distillation by bringing it into intimate contact with hot coal distillation gases to distill the tar and produce pitch of intermediate free carbon content therefrom.

In testimony whereof I affix my signature.
STUART PARMELEE MILLER.
